Primary Examiner — Richard E Chilcot(74) *Attorney, Agent, or Firm* — Venjuris, P.C.**CLAIM**

What is claimed is the ornamental design for a wireless electronic lock housing, described herein and graphically illustrated.

DESCRIPTION

FIG. 1 is a top right isometric view of the wireless electronic lock housing shown with a serrated pin catch;

FIG. 2 is a top right isometric view of the wireless electronic lock installed in a cupboard, shown with top of cupboard cut away for clarity;

FIG. 3 is a front view of the wireless electronic lock housing. The serrated latching pin is omitted for clarity;

FIG. 4 is a right view of the wireless electronic lock housing. The serrated latching pin is omitted for clarity;

FIG. 5 is a left view of the wireless electronic lock housing. The serrated latching pin is omitted for clarity;

FIG. 6 is a top view of the wireless electronic lock housing. The serrated latching pin is omitted for clarity;

FIG. 7 is a top left isometric view of the wireless electronic lock housing. The serrated latching pin is omitted for clarity;

FIG. 8 is a bottom left isometric view of the wireless electronic lock housing. The serrated latching pin is omitted for clarity;

FIG. 9 is a bottom right isometric view of the wireless electronic lock housing. The serrated latching door pin is omitted for clarity; and,

FIG. 10 is a rear view of the wireless electronic lock housing. The serrated latching door pin is omitted for clarity.

The broken/dashed lines represent environmental matter and form no part of the claimed design.

1 Claim, 5 Drawing Sheets(56)
